UNITED STATES PATENT OFFICE.

VICTOR W. KLIERSRATH, OF EAST ORANGE, NEW JERSEY, ASSIGNOR TO THE SIMMS MAGNETO COMPANY, OF EAST ORANGE, NEW JERSEY, A CORPORATION OF NEW JERSEY.

SYSTEM OF INTERSELECTIVE DISTRIBUTION OF SECONDARY ARMATURE-CURRENTS.

1,369,342.

Specification of Letters Patent. Patented Feb. 22, 1921.

Application filed December 30, 1918. Serial No. 268,791.

To all whom it may concern:

Be it known that I, VICTOR W. KLIERSRATH, a citizen of the United States, residing at East Orange, in the county of Essex 5 and State of New Jersey, have invented certain new and useful Improvements in Systems of Interselective Distribution of Secondary Armature-Currents; and I do hereby declare the following to be a full, clear, 10 and exact description of the invention, such as will enable others skilled in the art to which it appertains to make and use the same.

My invention consists in the novel features hereinafter described, reference being had to the accompanying drawing which illustrates diagrammatically two embodiments of the invention selected by me for purposes of illustration, and the said invention is fully disclosed in the following description and claims.

The distribution of high tension magneto current to the ignition plugs of internal combustion engines having a large number 25 of cylinders has necessitated changes in the ordinary distributor, especially where more than eight cylinders are used in the engine, as the construction of magneto generators imposes certain limitations as to the speed 30 at which the armature, periodic interrupter, and the rotary part of the distributor may be practically and successfully operated, and also as to the size of the stationary portion of the distributor, in which the stationary 35 conducting members, which are connected to the spark plug, are located. It has therefore been proposed to arrange the stationary conducting members of the distributor in two circular series instead of one and to 40 provide two rotary distributing members, each coacting with one of said circular series of conducting members and operating alternately, the rotating conducting member of one section of the distributor being 45 in an intermediate position between two stationary conducting members when the rotating conducting member of the other section of the distributor is in operative relation with a conducting member of its circular series. It has been found, however, 50 that in a system arranged in the manner described wherein both of the rotating distributing members are in connection with the secondary coil, difficulty is experienced

by arcing between the rotating conducting members and stationary conducting members when not in the predetermined operative relation, resulting in improper firing of the engine cylinders. It has therefore been appreciated that some method of interselection is required in order to avoid this difficulty and to insure that the current from the secondary winding shall be distributed by the rotary conducting members of the distributor only as each comes into a predetermined operative relation with a stationary conducting member of its appropriate circular series without, however, increasing to any material extent the speed of the armature shaft of the magneto. 70

The object of my invention is to provide extremely simple and efficient means for such interselection whereby it may be accomplished through the agency of a slip ring on the armature shaft permanently 75 connected to one end of the secondary winding of the armature, the other end of the secondary winding being permanently grounded at all times and preferably by being connected to the primary coil. In 80 carrying out my invention therefore, I employ in connection with the armature, a slip ring having its bearing surface provided with a plurality of short metal conducting segments of like polarity arranged 85 in the same plane transversely to the axis of the armature, or in other words, in the same circular brush engaging path, separated by non-conducting surfaces which are preferably of such character as to wear uniformly 90 with the metal segments, and which eliminate carbonization of their insulated surfaces due to the rubbing contact of carbon of similar brushes, and to employ in connection therewith two carbon brushes so disposed that only one of the same can be in contact with a metallic segment of the slip ring at a time, and to connect each of said 95 brushes independently to one of the rotary conducting members of the distributor, which rotary members are insulated from each other. The relative rotation of the armature slip ring and of the rotary members of the distributor is such that whenever 100 one of said rotary conducting members of the distributor is in operative relation with one of the circular series of stationary conducting members with which it coöperates, 105

the brush connected with such rotary member of the distributor will be in contact with a metal segment of the slip ring, and therefore the other brush which is connected to the other rotary distributing member will be upon a nonconducting portion of the ring, so that no current can pass to the other rotary distributing member. This insures an accurate inter-selective action, and precludes the possibility of arcing at either of the rotary distributing members or the distribution of current therefrom when not in proper operative relation with the selected stationary conducting member, and the proper firing of the engine cylinders is therefore accurately secured. It will be understood that the magneto armature and the periodic interrupter therefor will be so constructed as to produce a number of sparks per revolution of the armature equal to the number of segments of the slip ring, multiplied by the number of brushes engaging the slip ring.

Referring to the accompanying drawings, Fig. 1 represents diagrammatically an embodiment of my invention which I have successfully employed in connection with a twelve cylinder internal combustion engine, selected by me for purposes of illustration, Fig. 2 represents a cross section of the slip ring indicated diagrammatically in Fig. 1, the position of the brushes being indicated in dotted lines,

Fig. 3 represents a similar diagrammatic representation as Fig. 1 of an embodiment of my invention which I have successfully employed in connection with an internal combustion engine having sixteen cylinders.

Fig. 4 represents a cross section of the slip ring indicated diagrammatically in Fig. 3, the position of the brushes being indicated in dotted lines.

Referring to Figs. 1 and 2 of the accompanying drawings, 1 represents the primary winding of a high tension magneto armature having one end connected to ground as at 2, and the other end connected to one of the separable contacts 3 of a periodic interrupter, the movable contact of which is indicated at 4, and which is connected to ground, as at 5. 6 represents the usual condenser which is preferably employed in connection with the magneto armature. 7 represents the secondary winding, one end of which is permanently grounded, preferably by connecting it with the primary winding, as shown in the diagram. The other end of the secondary winding is connected by wire 8 or other suitable connection with metallic segments of my improved slip ring, which is carried by and rotates with the magneto armature, said segments being indicated at 9-9. In the formation of this slip ring I prefer to provide a metallic circular body 10, as shown in Fig. 1, having the segments

9 formed integral therewith, and provided with over-hanging extremities or shoulders 11-11, as shown, the said ring being embedded in a body or spool 12 composed of insulating material, and which will conveniently be provided with a central aperture 13 to fit the armature shaft. The body of the spool is also preferably provided with flange portions 14-14 of greater diameter than the ring 10, forming an annular groove 75 into which the brushes, hereinafter described, project. The spool 12 is also provided with an insulating sleeve 12^a through which the electrical connection 8 from the secondary winding extends to the slip ring, 80 as shown in Fig. 2. The exterior of the metal ring 10 between the segments 9-9 is provided with insulating brush engaging material 15-15 forming two segmental insulating surfaces concentric with the outer faces of the segments 9-9, but being of considerably greater extent in a direction around the ring. I prefer to form the body of the spool of hard rubber on account of its great insulating value per unit of thickness, and to make the insulating brush engaging segments of a rubber base combined with foreign material, which will produce the highest possible insulating value, while affording a wearing surface which will substantially equal the wear resistance of the metal segments 9-9, and which will eliminate carbonization of the insulated surfaces due to the rubbing contact of a carbon or other brush of similar composition. 16 and 17 represent two brushes of carbon or other suitable material, which may be of any usual or preferred construction. These brushes are supported stationarily in such position that only one of them can be in contact with a segment 9 of the slip ring at a time, and preferably in such position, that as shown in Fig. 1, when one of said brushes is in contact with a metallic segment 9, as the brush 16, the other brush, as brush 17, will be in the center of one of the insulating segmental portions 15, as therein shown. In the embodiment of my invention arranged for a twelve cylinder engine, as shown in Fig. 1, I prefer to employ a slip ring having two conducting segments 9 disposed opposite to each other, or at 180° from each other, and to arrange the brushes 16-17 at right angles to each other, or at an angle of 90° from each other. It will be seen that as the slip ring rotates with the armature, each segment will make contact with the brushes 16-17 alternately during a revolution, thus producing four contacts, it being understood that the armature in this case and its periodic interrupter are so constructed as to obtain four sparks per revolution of the armature.

The distributor comprises two circular series of stationary conducting devices indi-

cated at 18—19 respectively, which may be insulated in any usual manner, each of said conductors being connected in any usual or well known manner with one of the spark 5 plugs of the engine. The spark plugs are indicated at 25 and 26. The rotary member of the distributor which may be of any desired character is indicated at 30 and is provided with a rotary conducting member for 10 each of the circular series of stationary conducting members, the said rotary conducting members being insulated from each other and being indicated in the diagram at 21 and 22, one of the rotary conducting members, as 21, being connected, as by wire 23, with the brush 16, the other rotary conducting member, as 22, being connected, as by wire 24, with the brush 17. The distributor may be operatively connected with 20 the magneto itself or may be separated therefrom and otherwise driven from the engine, but in any case it is obvious that it must be operated in timed relation with the slip ring 10 so that as each of the brushes 25 16 and 17 alternately engages one of the segments 9 of the slip ring, the rotary conducting member of the distributor connected with such brush will be in operative relation to one of the stationary conducting members of the distributor, thus making the ratio of rotation one for the distributor to three for the magneto armature shaft, where ignition is furnished to one half cylinder engine.

35 The method of distribution which I prefer to employ is that known as the "jump spark" method of distribution, in which a circular series of radial pins of non-oxidizable or practically non-oxidizable material are employed in connection with a rotating conducting element also of non-oxidizable or practically non-oxidizable material, which rotates without actually contacting, a clearance of approximately .012 to .017 being provided. This form is preferable to those employing a rubbing contact in that it eliminates entirely troubles due to leakage from one distributor segment to another, due to the wearing of the carbon 40 brush and the depositing of a carbon surface between the segments of the distributor.

50 In order that the rotary conducting members of the distributor shall be brought alternately into operative relation with one of its circular series of stationary conducting members, it is necessary to offset either one of the circular series of stationary contacts, or its corresponding rotary conducting member. It is found to be more convenient 55 to offset one of the rotary conducting members from each other, and where each section of the distributor is provided with these stationary conducting members, as herein indicated, distributed uniformly 60 around its circumference and separated

therefore a distance of 60° from each other, the rotary conducting members of the distributor will be offset 30° . I prefer to place the rotary conducting members 21—22 on opposite sides of the axis of rotation, and 70 to offset them 30° from a diametrically opposite position, as shown in Fig. 1, so that the angle between the two rotary conducting members, on one side, will be 150° , and on the other side 210° , thus affording an offset 75 of 30° from 180° .

In the operation of the magneto, as will be clearly apparent in Fig. 1, in which the brush 16 is shown in contact with one of the segments 9 of the slip ring, the high 80 tension secondary current will pass through the connection 23 to the rotary conducting member 21 of the distributor, passing thence to the stationary contact with which it is in operative relation and thence to the spark 85 plug connected therewith at which time the rotary conducting member 22 is in position midway between the two stationary conducting members of the other section of the distributor, and at which time the brush 17 90 connected therewith is upon the insulated portion 15 of the slip ring, so that no current can pass to the rotary conducting member 22. When the segment 9 is in contact with the brush 17, current will pass through 95 the connection 24 to the rotary conducting member 22, at which time it will be in operative relation with one of the stationary conducting members of its circular series, and passing thence to said stationary conducting member, will be conducted to the spark plug connected therewith, at which time the rotary conducting member 21 will be in a position midway between two of its 100 circular series of stationary conducting members, and its brush 16 will then be in contact with an insulated portion 15 of the slip ring.

Referring now to Figs. 3 and 4 which illustrate an embodiment of my invention 110 which I have found especially desirable for use with engines having sixteen cylinders, 101 represents the primary winding, one end of which is connected to ground, as at 102, and the other end of which is 115 connected to ground as at 105, through the periodic interrupter 103—104, the condenser 106 being interposed in the usual manner, 107 illustrating the secondary winding, and 108 the connection to the slip ring, all 120 as hereinbefore described with reference to Figs. 1 and 2. In this instance the slip ring shown in Fig. 3 and in section in Fig. 4, comprises a metal ring 110 provided with three segmental brush engaging portions 109, distributed at 120° apart about the axis of the ring, and embedded in an insulating body 112 having the shaft aperture 113 and flanges 114 as previously described, 125 the peripheral portions of the slip ring be- 130

ing provided with secondary insulating brush engaging portions 115 between the conducting segments, as clearly shown in Fig. 3. 116—117 represent the brushes which in this instance are conveniently arranged diametrically opposite each other, so that whenever one of said brushes is in contact with one of the conducting segments 109, the other brush will engage the center of one of the insulating portions. In this construction six contacts will be made in each revolution of the slip ring, it being understood that the armature and periodic interrupter are so constructed as to produce six sparks at each revolution of the armature.

118—119 represent the two sections of the distributor, each provided in this instance with eight radially disposed stationary conducting members, distributed at equal distances around the center at intervals of 45° , and each connected to one of the spark plugs, which are herein indicated at 125 and 126. 120 represents the rotary part of the distributor carrying the rotary conducting members 121, 122, insulated from each other and connected respectively by the connections 123 and 124 with the brushes 116 and 117. In this instance as the separation between the stationary conductors of the circular series is represented by 45° , one of the rotary conducting members 121 and 122 is off-set from the other $22\frac{1}{2}^\circ$, and I prefer to locate them at opposite sides of their axis of rotation and to offset them $22\frac{1}{2}^\circ$ from a diametrically opposite position, making the angle between them on one side $157\frac{1}{2}^\circ$, and on the other side $202\frac{1}{2}^\circ$, as will be readily understood.

40 The operation of the apparatus indicated in Figs. 3 and 4 will be as before described with reference to the construction indicated in Figs. 1 and 2, except that the slip ring will make its contacts with the brushes 116 and 117 alternatively distributing current interselectively and alternatively from the rotary conducting members 121 and 122 to the sixteen spark plugs of the engine and at all times when current is passing over 45 one of the connections 123 or 124, to one of the rotary conducting members 121 or 122, the brush connected with the other rotary conducting member will be in engagement with one of the insulating segments 115, thus preventing the flow of any current therethrough. As there will be six contacts made at the slip ring in each revolution thereof, the ratio of rotation between the rotary members of the distributor and the armature shaft will be as follows, to wit, one revolution of the distributor members to two and two thirds revolutions of the magneto armature to furnish ignition to a sixteen cylinder engine.

60 65 I do not limit myself to the particular

number of metallic segments on the slip ring or the particular number and arrangement of stationary conducting members in the circular series of stationary conducting members of the distributor, as these may be varied according to the number of cylinders in the engine to be fired and the gear connections for driving the magneto armature and the distributor. As previously stated, it is immaterial whether the rotary conducting members of the distributor are connected with and driven from the armature shaft, or whether the distributor is separated from the magneto and the rotary members thereof are driven from the engine, it being only necessary that the proper timed relation shall be maintained between the slip ring and the rotary conducting members of the distributor so that as each brush engages a metallic segment of the slip ring, the rotary distributing member connected therewith shall be in operative relation with one of its circular series of stationary conducting members, while the other rotary distributing member shall be in a position out of operative relation with any of its circular series of conducting members, and preferably midway between two of the same.

The form of my invention illustrated in Figs. 1 and 2, for example, is the preferred form for a twelve cylinder engine, and the form of my invention shown in Figs. 3 and 4 is the preferred form for use with a sixteen cylinder engine, but either form can be used with engines having eight cylinders or more.

Where engines having twelve, sixteen, or any other number of cylinders are so constructed as to require irregular firing, the rotary distributing members will be offset at the proper angle to accommodate the same.

It will be noted that by employing a plurality of segments on the slip ring in connection with the brushes connected independently to the separate rotating distributor members, the said brushes being located so that only one at a time is in contact with any segment of the slip ring, the speed of the armature of the magneto can be maintained at a very low rate, even when the invention is employed in connection with engines having twelve, sixteen, and more cylinders.

What I claim and desire to secure by Letters Patent is:—

1. In a system of interselective distribution of secondary armature currents, the combination with a distributor, comprising a plurality of circular series of stationary conducting members, a rotary conducting member for each series, said rotary members being insulated from each other, and connected for joint rotation, of a magneto having its armature provided with a pri-

mary winding, and a secondary winding having one terminal thereof permanently grounded, a rotary part operating in timed relation with the magneto armature and 5 said members of the distributer, and provided with a circular brush engaging path, a plurality of separate contacts located in said path and connected to the other terminal of the secondary winding, a plurality 10 of brushes, one for each of the rotary members of the distributer, for engaging said circular path and all of said separated contacts therein, and a connection from each of said brushes, to one of said rotary distributer members, said brushes being so located 15 that only one of the same is at any time in engagement with any of said contacts in said circular path, said magneto being constructed to produce a number of sparks per 20 revolution of the armature thereof equal to the number of said separate contacts in the brush engaging path, multiplied by the number of brushes engaging said path.

2. In a system of interselective distribution of secondary armature currents, the 25 combination with a distributer, comprising a plurality of circular series of stationary conducting members, and a rotary conducting member for each series, said rotary 30 members being insulated from each other

and connected for joint rotation, only one of said rotary members at a time being capable of assuming operative relation with any one of said stationary conducting members of the distributer, of a magneto having 35 its armature provided with a primary winding and a secondary winding, having one terminal thereof permanently grounded, a slip ring on the armature shaft having a peripheral brush engaging path, a plurality 40 of separated conducting segments located in the said path and in a plane transverse to the axis of the armature shaft and connected at all times to the other terminal of the secondary winding, a plurality 45 of brushes for engaging all of the slip ring segments, a connection from each brush to one only of the rotary distributer members, said brushes being located around the slip ring so that only one of the same is capable 50 of being in engagement with any segment of the slip ring at a time, said magneto being so constructed as to produce a number of sparks per revolution of the armature, equal to the number of said segments of the 55 slip ring, multiplied by the number of said brushes engaging said slip ring.

In testimony whereof I affix my signature.

VICTOR W. KLIESRATH.
